UNITED STATES PATENT OFFICE

152,277

DESIGN FOR A BOOTH

Charles N. Manville, Lynwood, Calif.

Application December 12, 1946, Serial No. 135,436

Term of patent 3½ years

(Cl. D13—1)

To all whom it may concern:

Be it known that I, Charles N. Manville, a citizen of the United States, residing in Lynwood, in the county of Los Angeles and State of California, have invented a new, original, and ornamental Design for a Booth, of which the following is a specification, reference being had to the accompanying drawing, forming part thereof:

The figure is a perspective view of a booth, showing my new design.

The rear wall of the booth is plain and unornamented. The dominant features of the design are embodied in the parts shown in full lines.

I claim:

The ornamental design for a booth, substantially as shown and described.

CHARLES N. MANVILLE.
